SEWING MACHINE

Allister S. Mitchell, Oakland, Calif., assignor to
 National Automotive Fibres, Inc., Detroit, Mich.,
 a corporation of Delaware

Application August 10, 1931, Serial No. 556,270

3 Claims. (Cl. 112—2)

This invention relates particularly to sewing machines for sewing "skips" in the seams of manufactured pleated, stuffed upholstery.

The primary object is to provide a simple, effective machine for completing any defective seams in pleated upholstery, such as is used in automobile seat-cushions, back-cushions, etc.

More especially, the present invention is intended to provide a machine particularly suited to sewing a ridge-seam or a portion of a defective ridge-seam between the pleats of a cushion which has been made on an upholstery machine having multiple sewing-heads and in which the sewing is imperfect due to breakage of a thread, or the like.

In a preferred embodiment, the cushion to be mended rests on a table having a ridge-like apex, and a movable ridge-bar is used to hold the seam in sewing position. The ridge-bar may be lowered to permit the work to be positioned, and may then be raised to bring the seam-ridge of the upholstery to sewing position.

The invention is illustrated in a preferred embodiment in the accompanying drawings, in which:

Fig. 1 is a front elevational view of a machine embodying the invention, and shows brokenly a cushion resting on the sewing-table; Fig. 2, a side elevational view of the machine; Fig. 3, a broken end elevational view showing the ridge-bar, taken as indicated at line 3 of Fig. 1; Fig. 4, a front elevation of the shuttle-housing and seam-engaging shoe, taken as indicated at line 4 of Fig. 10; Fig. 5, a broken side elevational view showing the sewing mechanism; Fig. 6, a plan view of the sewing mechanism; Fig. 7, a broken side vertical sectional view of the clutch mechanism; Fig. 8, a broken rear elevational view of the machine, showing the belting arrangement and bobbin winder; Fig. 9, fragmentary view, similar to Fig. 8 but showing the bobbin winder in operating position; Fig. 10, a broken vertical sectional view showing the seam-engaging shoe and a pleated cushion in sewing position; Fig. 11, a broken detail view showing the sewing needle and walker-foot; Fig. 12, a plan sectional view of the mechanism for operating the needle-bar and walker-foot; and Fig. 13, a broken sectional view, taken as indicated at line 13—13 of Fig. 12.

In the embodiment illustrated, A designates a main frame comprising standards A', a bed A², a machine supporting member A³, which is rigidly connected to a cross-bar A⁴, and a work-supporting centrally ridged table A⁵; B, a ridge-bar, mounted at the apex of the table A⁵; C, a sewing

machine having its needle disposed horizontally; D, a bobbin-threading device; E, a friction clutch; F, a motor for driving the sewing machine; and G, a thread-supporting device.

The main frame of the machine may be of any suitable construction, but a supporting member A³ and cross-bar A⁴ are formed, preferably, of channel iron to provide a strong and rigid support for the sewing mechanism. The table A⁵ is shown having an inverted V-shape which has been found very advantageous, although other shapes may be used if desired. The table is provided with a sheet metal covering 10, to permit the work to be slid over the table easily, and the back portion of the metal covering is turned upwardly to form a guard for the mechanism in rear of the table.

A standard 11 at one end of the table supports a pivot 12 for one end of the ridge-bar B, and another standard 13 at the other end of the table 10 is slotted to form a guide for the bar and is provided with a recess 14 adapted to receive a compression spring 15 which urges the bar into its uppermost position by a saddle-like member 16. The upper portion 17 of the bar B is narrowed 25 so as to form a narrow ridge, and the bar has a notched portion 18, to avoid the sewing needle and walking foot, as shown in Fig. 4. A wire 20^a serves to connect the bar B with a treadle 20 which permits the bar to be depressed at will. 30

A sewing machine C is rigidly bolted to the supporting member A³. The machine is of standard construction except that it is mounted to sew horizontally instead of vertically and is equipped with a special seam-engaging shoe. The usual 35 shuttle, bobbin 21, and driving mechanism are provided within a housing 22. A seam-engaging shoe 23 is mounted on the housing and has a pair of U-shaped wires 23^a to confine a seam-ridge in sewing position. The wires afford an opening 40 through which the needle 24 sews the fabric.

As shown in Figs. 12—13, the needle 24 is rigidly connected to a needle-bar 24^a which is slidably mounted within a supporting member 24^b which is pivotally connected at 24^c to a housing 27. The 45 needle bar is driven by a pitman 24^d which is pivotally connected to the bar at 24^e.

The supporting member 24^b is oscillated about its pivot 24^c by means of a pitman 24^f, pivotally connected at 24^g to the supporting-member and pivotally connected to a rock-arm 24^h and drive-arm 24^j at 24^k. The rock-arm 24^h is pivotally connected to the housing 27 at 24^l. A cam-bar 24^m is attached to the housing 27 and has an 55

S-shaped slot in which a stud 24^a on the drive-arm 24^b travels.

A walking foot 25, having a perforation 25^a through which the needle reciprocates, is mounted on a push rod 25^b which also is slidably mounted in the supporting member 24^b so that the push-rod and needle-bar are always in parallel relationship. The push-rod has a pivotally mounted slide-block 25^c, driven by a slotted rock-member 10 25^d which is pivotally connected at 25^e to a pivot carrying member 25^f. The rock-member 25^d is driven by a rock-member 25^g through a slot-and-block connection at 25^h. One end of the rock-bar 25^c is pivoted at 25ⁱ to the housing 27, and the other end makes a pivotal connection at 25^k with a pitman 25^l.

In order that the walking-foot 25 may be moved from engagement with the fabric, the pivot-carrying member 25^f is fixedly mounted on a tubular slide 25^m which extends through an opening in the housing 27. The tubular slide is urged outwardly by means of a compression spring 25ⁿ whose tension is regulated by means of a plunger 25^p which extends into the slide and has an adjustable threaded connection with the housing 27 at 27^q.

The sewing mechanism is provided with a fly-wheel and sheave 28, which is mounted on a shaft 29. The lower end of the shaft 29 is provided with an eccentrically mounted disk 29^a which rotates within a ring 29^b to which the pitman 24^d is connected at 29^c, the drive-arm 24^b is connected at 24^a, and the pitman 25^l is connected at 29^d. Thus it will be understood that rotation of the shaft 29 oscillates and reciprocates both needle and walking-foot so that a fabric may be sewed and fed along by the same.

The fly-wheel 28 has a sheave portion which is driven by a belt 30 which passes over deflecting sheaves 31 and around a clutch wheel 32. The needle may be withdrawn from the fabric by manual turning of the fly-wheel.

Provision is made for retracting the spring-held walking-foot 25 by means of a rock-arm 33 acting on the pivot-carrying member 25^l. A spring 33^a tends to release the walking-foot in fabric engaging position. A rock-shaft 34 is connected to the treadle 20 by means of a wire 20^b and the shaft, in turn, actuates the rock arm 33 through a wire connection 20^c. By providing a proper amount of slack in the wire 20^a, the walking-foot will be retracted before the ridge-bar is lowered.

In the rear of the machine, as shown in Figs. 8 and 9, the device D serves to load an extra bobbin with thread at about the same rate that thread is expended from the bobbin in the machine. A shaft 35 is adapted to receive the bobbin and is equipped with a sheave 36 adapted to engage the belt 30. The shaft is pivoted from the bed A² at 37 by means of an L-shaped arm 38. A pair of toggle arms 39 and 40 are pivotally connected at 41 and are used to swing the sheave into belt-engaging position. The arm 40 is pivoted to the frame at 42 and is provided with a lug 43 which may serve as an operating handle as well as a toggle-stop. The toggle arm 39 is provided with an integrally formed pivot 44, which connects it to the arm 38. To this pivot is fastened rigidly a spring-guide 45 by means of a small bolt 46. The guide serves to hold the bobbin on the shaft and also serves to guide thread onto the bobbin smoothly and uniformly.

The clutch E is of known construction and is supported by a bracket 49 suspended from the

bed A². The sheave 32 is journaled on a shaft 50 and is provided with a friction face 51. A companion disc 52, having a fabric facing 52^a, is slidably keyed to the same shaft and actuated by a throw-out yoke 53. The yoke is connected to a rock arm 54, which is pivoted at 55 to the bracket, and is provided at one end with a brake 56 adapted to engage the sheave when the discs are thrown out of engagement; the other end of the arm is connected to an operating crank 57 by means of a link 58. This crank and an additional crank 59, are both fixedly mounted on a shaft 60 which is journaled in brackets 60^a mounted on the bed A². A treadle 61 is connected to the crank 59 by means of a wire 61^a and actuates the clutch mechanism. A tension spring 62 tends to disengage the clutch.

The motor F is mounted on the lower side of the bed and drives a sheave 63 on the clutch shaft 50 by means of a belt 64.

The thread supporting device G is mounted on top of the sewing machine and comprises a spindle 65 and a spool-supporting shelf 66 which carries a sewing-thread spool 67 and a bobbin-thread spool 68. A sewing thread 67^a is led from the spool 67 over suitable guides 69 and tensioning devices 70 to the sewing needle; and a bobbin-thread 68^a is drawn from the spool 68 over guides 71 and a tensioning device 72 to the bobbin-winder, as will be readily understood from the drawings.

To operate the device, the operator turns the wheel 28, until the sewing needle is retracted, and depresses treadle 20, which retracts the walking-foot and lowers the bar B. A cushion is then laid over the bar B so that a ridge is formed in the fabric in the desired position, and the treadle is then released which permits the bar to press the ridge into the shoe 23. Upon depressing treadle 61 the clutch is permitted to engage and the machine starts to sew a horizontal ridge-seam, which will catch both a cover and lining fabric to form a pleat, as shown in Fig. 10. The operator pushes the work along under the shoe, aided by the feeding action of the walker-foot, until the desired length is sewed and the treadle 61 may be released. After retracting the needle, the treadle 20 is again depressed which permits the completed work to be removed from the machine. If during the sewing operation, the bobbin winder D is thrown to the position indicated in Fig. 9, a loaded bobbin will be ready when the bobbin in the machine is empty.

The machine is very easy to operate and provides a rapid method of remedying any imperfect sewing in a cushion. The stitches are made uniformly, in straight lines, and any need for hand-sewing is obviated.

The operator stands in front of the machine (presented in Fig. 1) and the cushion, during the sewing operation, is fed in a direction parallel with the front of the machine. The control pedals are accessible at the front side of the machine, as appears in Fig. 2. The body of the sewing machine C extends forwardly from the supporting standard A³, as will be understood from Figs. 2 and 5. Thus, the body of the sewing machine frame is horizontally disposed, and the head 27 which contains the needle-operating mechanism and the walking-foot operating mechanism depends from the front end of the main body of the sewing machine, and the needle and walking-foot are presented rearwardly at about the level of the ridge-bar B, while the housing 22 which contains the bobbin 21 is disposed back 75

of the ridge-bar. As will be noted from Fig. 2, the ridged table 10 has a rear edge portion of trough-like form, and the standard A³ rises from the rear portion of the trough. The arrangement described is well adapted to the purpose of sewing the ridge-like seams of a defective cushion, as will be readily understood from Fig. 10. That is, where stitches have been missed in forming any particular seam of a cushion in the manufacture thereof in the regular cushion-making machine, the necessary repair of the cushion can be readily effected by means of the improved machine herein shown.

The foregoing detailed description is given for clearness of understanding only and no unnecessary limitations should be understood therefrom, but the appended claims should be construed as broadly as permissible, in view of the prior art.

What I regard as new, and desire to secure by Letters Patent, is:

1. In a machine of the character set forth: a frame embodying an elongated ridge-like cushion-supporting table equipped at the apex of the ridge with a longitudinal ridge-bar providing a straight edge which extends parallel with and is accessible from the front side of said frame; a standard rising from the rear portion of said table; a sewing machine supported on said standard and having its body extending forwardly over said ridge-bar and having the front end of said body equipped with a depending head housing a sewing needle and actuating means therefor, said sewing needle having its piercing end presented rearwardly and perpendicular to said ridge-bar; and treadle means for raising and lowering the ridge-bar, said means being accessible to an operator located in front of said frame.

2. In a machine of the character set forth: a frame embodying a ridge-like cushion-supporting table extending parallel with the front side of the frame and a standard disposed at the rear of and rising above the elongated apex of said table; a 5 depressibly mounted elongated ridge-bar at the apex of said table providing a straight edge adapted to support an upwardly presented cushion-seam when the cushion is supported on said table; a sewing machine mounted on said stand- 10 ard and having a forwardly extending body projecting over and across said table, said body carrying a depending head; a sewing needle and a walking-foot carried by said head and presented towards one vertical side of said ridge-bar; 15 actuating-mechanism within said head serving to actuate said sewing needle and walking-foot; driving mechanism serving to operate said actuating-mechanism; and a forwardly presented manually operable pedal serving to retract said 20 walking-foot and depress said ridge-bar, at will.

3. In a machine of the character set forth: a frame embodying a cushion-supporting table equipped with a movable ridge-bar providing a straight edge extending parallel with the front 25 side of the frame and substantially unobstructed at both ends; a sewing machine supported on said frame extending over and across said table, said sewing machine being equipped with a sewing needle and a walking-foot presented rear- 30 wardly towards said ridge-bar so as to cooperate with one vertical side thereof to feed cushions thereon; and manually controlled means for retracting said ridge-bar downwardly and said walking-foot forwardly. 35

ALLISTER S. MITCHELL.
